BRAIDING MACHINE

Alfred Gamba, Wildegg, Switzerland

Application April 4, 1934, Serial No. 718,988
In Switzerland December 9, 1932

6 Claims. (Cl. 96—12)

The present invention relates to the arrangement of raceways in braiding machines and consists in providing the base portions of the carriers with adjustable trip fingers which in cooperation with trip fingers established at the crossings of the raceways will displace certain switch plates to direct the path followed by the carriers.

The annexed represents a working example of the invention. Therein are:

- 10 Fig. 1 a plan of the general arrangement,
Figs. 2 and 3 vertical sections on the lines II—II
and III—III in Fig. 1,
Fig. 4 a plan of a parallel movement and
Figs. 5 and 6 plans of fittings for the trip fingers,
15 The Figs. 7, 7a, 7b and 7c, 8, 8a, 8b, 8c and 8d
and 9, 9a, 9b, 9c, 9d and 9e, are diagrammatical
views relating to particular arrangements of the
raceways.

Fig. 7 represents nine raceways arranged in
20 three rows which are touching each other and
are available for two groups of bobbin carriers.

Figs. 7a and 7b represent two paths which can
be followed simultaneously by the two groups of
25 bobbin carriers and Fig. 7d represents the ar-
rangement of trip fingers required for obtaining
a safe working of the groups of bobbin carriers.

Fig. 8 represents six raceways arranged in two
rows and which are available for three groups of
bobbin carriers.

30 Figs. 8a, 8b and 8c show the three paths fol-
lowed simultaneously by said groups and

Fig. 8d shows the corresponding arrangement
of trip fingers.

Fig. 9 represents nine raceways arranged in
35 three rows which are touching each other and
are available for four groups of bobbin carriers.

Figs. 9a, 9b, 9c and 9d show the four paths
followed simultaneously by said groups and

Fig. 9e shows the corresponding arrangement
40 of trip fingers.

The circular raceways 1 for the carriers 2 are
disposed on a circle and cut into a plate 3. The
quoit plates 4 are arranged above the raceway-
plate 3 while the driving gears 5 are mounted
45 rotatably in a recess 6 of said plate and on the
supporting posts 8 screwed fast to a base plate 7.
Into the carrier axis on the base portion of
the carrier and above the two flanges 9
which embrace the quoit plate 4 are stuck four
50 exchangeable trip fingers or pins 10 above one
another. These fingers are clamped fast by means
of set screws 11 and are extended with their ends
to the same distance from the carrier shaft 25
and radially to the raceway in which said carriers
55 are guided by shuttles 19.

Corresponding trip fingers 12 are provided on
the axles 13 of switch tongues 14 which axles
carry said trip fingers clamped fast between
washers 15 by means of nuts 16 said switch
tongues being located in recesses of the raceway-
60 plate and facing each other on the common tan-
gent line of the two circular raceway. These
trip fingers 12 are tongue shaped as shown in
Fig. 5 and easily exchanged and inserted after
loosening the nuts 16. The axles of the two
65 switch tongues 14 extend into the recess 6 and
are made cooperative by means of two double
levers 18 connected by links 17 to form a parallel
movement. The swinging of one tongue 14 will
therefore force the other tongue to a swing in
70 an opposite sense and will establish thereby for
the shuttle 19 at the base of the carrier a cross-
ing from the one raceway 1 to the other. The
two levers 18 are coupled together by a strong
helical spring 20 attached to the hub portion of
75 said levers. The object of this arrangement is
to reestablish the exact normal median position
of the switch tongues after each displacing of
these tongues by the trip fingers of the carriers.
Any intermediate position of the tongues is there-
80 by prevented.

If it is desired to lock the position of the
tongues 14 in a given position this can be done
by means of a slide 22 located on the rim of
the raceway plate 3. One of the double levers
85 18 having a forked extension is attached by a
band 21 to the slide 22 which is guided by screws
26 engaged into a suitable slot of said slide. In
the median or normal position, as shown in Fig.
1, the band is bolted to a stop 23 by means of
a screw 24 and in the displaced positions the
slide may be fixed by tightening the screws 26.
In the median position the tongues of the shoes
of the spool carriers will travel in their respec-
tive circular raceways, while by a displacing of
95 the slide from the median position the bobbin
carriers may be turned off from one raceway to
the adjoining raceway.

Owing to the described arrangement of parts
especially of the coupled tongues and the trip
100 fingers it is possible to allot to each carrier a
predetermined path through the given system of
raceways and this only by inserting or removing
certain trip fingers at the tongues and the
carriers.

In the Figs. 7, 7a and 7b illustrating a race-
way system having eight raceways surrounding
a central one, the possible paths of two groups
of bobbin carriers are shown. Fig. 7a shows the
path for one group and 7b for the other. The
110

twelve switches are numbered 1 to 12 and of the two groups of carriers the group of six is marked with a circle and a point and the group of ten with a circle having a vertical diameter 5 line.

In the Fig. 7c the carrier axles are marked with I, II and the switch tongues with 1 to 12.

In a similar manner in the raceway system of the Figs. 8, 8a, 8b and 8c three different groups 10 of carriers may travel without collision simultaneously on the three paths shown in Figs. 8a, 8b and 8c and as in the first example each carrier will work automatically the different switch tongues.

15 The seven existing switch tongues are numbered 1 to 7 and the possible number of carriers is also 7, two groups of three and 1 group of one carrier. These carriers are marked by a circle with a point, a circle having a vertical diameter and a circle having a horizontal diameter. The axles of the carriers are marked with 20 I to III and the switch tongues with 1 to 7.

In the arrangement according to the Figs. 9, 25 9a, 9b, 9c and 9d there are four groups of carriers travelling four different paths. Here again are twelve switch tongues and numbered accordingly. The number of possible carriers is twelve, in four groups of three, marked respectively with a circle and point, a circle with vertical diameter, a circle with horizontal diameter and a circle with crossed diameters.

30 In each of the four groups there are three crossings. For the group 1 there are the crossings 3, 4, 6, for group 2 the crossings 2, 4, 7, for group 3 the crossings 6, 9 and 11 and for the group 4 the crossings 7, 9 and 10.

What I claim is:—

1. In an arrangement of raceways for braiding machines and in combination, a base plate and 40 supporting posts fixed to said base plates, driving gears having quoit plates attached thereto and mounted rotatably on said posts, and bobbin carriers adapted to be guided by said quoit plates, circular plates fixed to the base plate concentrically to the supporting posts and provided with circular raceways, exchangeable trip fingers provided on the base portions of said carriers,

vertical journalled axles established near the crossings of the raceways, and switch tongues fast to said axles, and removable trip fingers clamped between washers on said axles and adapted to be engaged by the trip fingers of the carriers to determine the path travelled by the carriers. 80

2. In an arrangement according to claim 1 and in combination, axles carrying trip fingers and arranged in pairs facing each other on the common tangent line of two adjoining raceways, the fingers on the two axles adapted to be engaged by the trip fingers of the carriers. 85

3. In an arrangement according to claim 1 and in combination, axles carrying trip fingers and arranged in pairs facing each other on the common tangent line of the two contiguous raceways and adapted to be engaged by the trip fingers of the carriers, and parallel movement members connecting said axles. 90

4. In an arrangement according to claim 1 and in combination, axles carrying trip fingers adapted to be engaged by the fingers of the carriers and arranged in pairs facing each other on the common tangent line of two contiguous raceways, two armed levers fast to said axles, parallel movement members connecting said axles and helical springs connecting the hub portions of said two armed levers forming parts of the parallel movement; said springs being adapted to reestablish after each displacing the initial position of said switch tongues. 100

5. In an arrangement according to claim 1 and in combination, bobbin carriers and switch tongue axles each provided with a corresponding number of exchangeable trip fingers adapted to be engaged by each other, said axles being arranged in pairs facing each other on the common tangent line of two contiguous raceways and said trip fingers being removable to establish combinations by which different paths are allotted to the single bobbin carriers. 110

6. In an arrangement according to claim 1 and in combination locking means on the outer edge of the base plate and adapted to fix an adjusted position of the switch tongues. 115

ALFRED GAMBA.
